DESIGN FOR A COMBINATION CAP AND EYE SHIELD

Samuel Feldman, Brooklyn, N. Y.

Application November 20, 1947, Serial No. 142,684

Term of patent 14 years

(Cl. D57—1)

To all whom it may concern:

Be it known that Samuel Feldman, a citizen of the United States of America and resident of the Borough of Brooklyn, city and State of New York, has invented a new, original, and ornamental Design for Combination Cap and Eye Shield, of which the following is a specification, reference being had to the accompanying drawing, forming part thereof, in which,

Fig. 1 is a top plan view of a combination cap and eye shield embodying my new design;

Fig. 2 is a cross-sectional view taken substantially along the line 2—2 of Fig. 1;

Fig. 3 is a bottom plan view thereof with a portion of the cap broken away; and

Fig. 4 is a bottom plan view similar to Fig. 3 but showing the eye shield part rotated from the

position shown in the said Fig. 3, to lie in a plane parallel to the vizor.

I claim:

The ornamental design for a combination cap and eye shield, substantially as shown and described.

SAMUEL FELDMAN.
